Attorney

UNITED STATES PATENT OFFICE.

EMMA A. WETZEL, OF JAMAICA, NEW YORK.

SECTIONAL STOVE.

Application filed April 18, 1922. Serial No. 554,452.

To all whom it may concern:

Be it known that I, EMMA A. WETZEL, a citizen of the United States, residing at Jamaica, in the county of Queens and State 5 of New York, have invented a new and useful Sectional Stove, of which the following is a specification.

The object of my invention is to provide a stove built up of sections and made up in 10 convenient and standard sizes and including a fire-place, some of the sections being provided with gas or electric heating fixtures, whereby a kitchen may be transformed into a dining room or living room.

15 It is a further object of my invention to provide a stove that is odorless and safe, which will take up little room, and which has an outdoor vent. It is also an object of my invention to provide means for concealing 20 the stove fixtures and give the invention the general appearance of an ornamental fireplace. It is also an object of my invention to provide a device that may be fitted into whatever space is available in connection 25 with a fireplace in a particular room.

I attain these and other objects of my invention by the mechanism illustrated in the accompanying drawings, in which—

Figure 1 is a front elevation of the invention;

Fig. 2 is a front elevation of the invention with the doors to the respective sections open, compartment 5 being shown without the heating coil;

35 Fig. 3 is a front elevation of a modified arrangement of the invention with portions of the apparatus broken away to show the position of the heating tank 20 and vent 23;

Fig. 4 is a front elevation of a modified arrangement of the invention positioned at one side of the chimney 27;

Fig. 5 is a vertical section on line 5—5 of Fig. 4;

Fig. 6 is a perspective view of one of the 45 sections removed;

Fig. 7 is a perspective view of another section of the stove compartment;

Fig. 8 is a perspective view of the removable screen or wall 24 which conceals the 50 ovens; and

Fig. 9 is a front elevation, reduced size, of a modified form of the invention, placed on a brick foundation.

Like numerals designate like parts in each 55 of the several views.

Referring to the accompanying drawings,

I provide a fireplace 1 containing a suitable fire-log of either gas or electric type. On either side of the fireplace I provide suitable ovens 3. I also provide a suitable boiler 20 in the compartments 9 and 22 extending through opening 21 in stove section 3, as shown in Fig. 3, adapted to heat a water coil 19 in the broiler compartment 5 of one of the ovens 3. I provide a suitable oven compartment 4; a suitable fireless cooker compartment 9, as shown in Fig. 2; and suitable storage compartment 10 arranged on either side of the fireplace 1, as illustrated in Figs. 2 and 3. I provide suitable doors 6, 7, 11 60 and 12 for the respective compartments, and provide suitable latches 8 for each of the doors. Positioned above the fireplace I provide a stove compartment 13 in which may be mounted a suitable gas or electric range 70 14. I provide suitable doors 15 for the stove compartment 13. The exterior surface of the various doors 6, 7, 11, 12 and 15, are ornamentally decorated or enameled in brick design to resemble and harmonize with the 75 brick walls of the fire-place, so as to conceal the ovens and present the appearance of a fireplace alone, as disclosed in Fig. 1. To further carry out the ornamental appearance of the stove as well as to increase its usefulness, I prefer to provide the mantel 2, as 80 shown in Figs. 1, 2 and 3. I prefer to provide the arcuate smoke hood 16 mounted on the pivots 17 and adapted to be swung out from its normal concealed position abutting 85 stop 18 to the position shown in Fig. 5 to divert odors from the food and from the gas or electric range up to the vent or flue 23.

As shown in Fig. 4, I may provide a removable screen 24 enameled or ornamented 90 with a brick design to correspond with the ornamental exterior surface of the respective doors of the stove sections and of the surrounding brick work of the fireplace to complete the ornamental design of the fireplace and at the same time to conceal the chimney flue 27 when the fireplace is arranged at one side of the chimney, as in the arrangement of the invention disclosed in Fig. 4. I may provide openings 28 between 95 oven 4 and range compartment 13, as shown in Fig. 3, for the escape of odors from the oven in the stove compartment 13 and thence up the vent or flue 23.

Referring to Fig. 9, there is illustrated a 110 modification of my invention having an oven compartment 25, similar to oven com-

partment 4 but positioned adjacent the stove compartment 13, which latter is of reduced size. This stove compartment 13 and oven 25, shown in Fig. 9, are placed on the brick foundation 26.

Referring to Fig. 3 of the drawings the complete use of the ovens is illustrated in this view, either gas or electric or any other suitable heating means may be employed. The 10 waste heat is utilized in heating the water in boiler 20, which in turn heats the oven 4. Odors from oven 4 escape from openings 28 into the stove compartment 13 and thence into the flue 23, and odors from the gas or 15 electric range 14 also are carried out through flue 23. The doors of the various stove sections are closed normally.

The smoke hood 16 is swung outward when the range is in use and is swung back 20 so as to permit of closing of the doors 15 when the range is not in use. The boiler section 9 can also be used as a warming oven.

In the form of the invention shown in 25 Fig. 2, the water heater 20 is replaced by a fireless cooker in compartment 9. The compartment 10 may be used as a storage compartment. The ovens at either side of the fireplace are identical in size and shape 30 and in the ornamentation of the doors so that any suitable interchanging of sections may be made as may be desired under any particular circumstances.

It is within the contemplation of my invention to make the doors and compartment 35 sections of any suitable material and to utilize any suitable uniform ornamentation for the exterior surfaces of the various doors and of the screen 24, if such a screen is utilized. 40

What I claim is:

1. In a sectional stove and fireplace combined, the combination of a fireplace, compartments arranged adjacent the fireplace, a range compartment positioned over the 45 fireplace, one of the first mentioned compartments functioning as an oven, openings from said oven into the range compartment, a flue disposed directly over the range compartment to dispose of odors from the oven, 50 and a removable screen arranged to conceal the flue, substantially as shown.

2. In a sectional stove and fireplace combined, the combination of a fireplace, ovens on either side of the fireplace, a range compartment positioned above the fireplace, a water heater positioned immediately over the fireplace and under the range compartment, a coil from said water heater positioned in a compartment of one of the ovens, 55 an oven compartment above said water coil, means for the escape of odors from the oven compartment into the range compartment, and means for the escape of odors from the range compartment to the chimney. 60

EMMA A. WETZEL.
